Primary Examiner — Cathron Brooks*Assistant Examiner* — Melanie Pellegrini(74) Attorney, Agent, or Firm — Middleton Reutlinger; Eric L. Johnson(57) CLAIM

The ornamental design for a helmet shaped pendant, as shown and described.

DESCRIPTION

FIG. 1 is a front perspective view of a helmet shaped pendant showing my design; and,

FIG. 2 is a rear perspective view thereof.

The broken lines shown in the drawings represent environmental matter and portions of the helmet shaped pendant which form no part of the claimed design.

1 Claim, 2 Drawing Sheets(56)
